Knight & Co. Inc.

UNITED STATES PATENT OFFICE.

CHRISTOPHER A. GARVEY, OF ST. LOUIS COUNTY, MISSOURI.

FOUNTAIN-BRUSH.

1,182,554.

Specification of Letters Patent.

Patented May 9, 1916.

Application filed January 31, 1916. Serial No. 75,296.

To all whom it may concern:

Be it known that I, CHRISTOPHER A. GARVEY, a citizen of the United States of America, a resident of the county of St. Louis, 5 State of Missouri, have invented certain new and useful Improvements in Fountain-Brushes, of which the following is a full, clear, and exact description, reference being had to the accompanying drawing, forming 10 a part of this specification.

My invention relates to improvements in fountain brushes, and the novel features are particularly adapted for use in stencil brushes and marking brushes. Prior to this 15 invention brushes of this kind have been provided with valves for controlling the flow of ink to the brush tips, and it has been quite difficult to prevent leakage at the valves. The ink is usually a thin fluid, very 20 difficult to confine in the ink reservoir, and a high degree of accuracy has, therefore, been required in forming the valves and valve seats. Moreover, such valves and their 25 seats are expensive, liable to get out of order, and the valves must be operated intermittently, in accordance with the judgment of the operator, to permit the ink to flow from the reservoir to the brush. Obviously, the 30 ink will flow from the reservoir at irregular intervals and in irregular quantities, and consequently the brush will be over-saturated at times and too dry at other times.

Therefore, an object of the invention is to produce a fountain brush consisting of an 35 ink reservoir and a few simple elements associated therewith in such a manner that the ink will flow substantially continuously from the reservoir to replace the ink discharged at the brush tip while the brush 40 is in service. The parts may be so adjusted that the desired flow of ink will be facilitated by the jarring action to which the brush is subjected when in use, and if desired the flow of ink may be accelerated by 45 a slight "throw" of the brush. The device is so constructed that the last mentioned action will not over-saturate the brush.

A most important object of the present invention is to produce a brush of this kind 50 having a highly efficient means for regulating the flow of ink from the reservoir to the brush. The new device preferably includes a body of absorbent packing material for retarding the flow of ink from the reservoir, and an adjusting device for compacting 55 and loosening this material so as to regulate

the flow of ink. To insure the desired results the body of packing material is preferably expandible and it may be either expanded or contracted by operating the adjusting device. The rate of flow of the ink may be increased by expanding the body of packing material through which the ink must flow in passing to the brush, and the flow may be retarded by compressing this packing material. 60 The packing material may be lamb's wool, or other material possessing inherent elastic qualities; or the elasticity may be obtained by securing the mass of material to an expansible spring, the object being to 65 regulate the flow of ink by expanding and contracting the packing material.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends 70 changes, variations and modifications which come within the scope of the claim hereunto appended.

Figure I is a side elevation, partly in section, illustrating a fountain brush embodying the features of my invention. Fig. II is a horizontal section on line II—II, Fig. I. Fig. III is a horizontal section on line III—III, Fig. I. Fig. IV is a horizontal section on line IV—IV, Fig. I. Fig. V is 80 an enlarged fragmentary view showing the expansible body of packing material whereby the flow of ink is retarded.

A designates an ink reservoir, closed at its upper end and provided with a screw 85 threaded lower end adapted to receive a brush holder B. A brush C is provided at its upper end with a threaded ring 1, the latter being screwed into the lower end of the brush holder B.

1' designates a gasket located between the brush holder and the top of the brush. A discharge passageway 2, formed in the brush holder B, constitutes a packing chamber, and the ink must flow through this packing 105 chamber in flowing from the reservoir to the brush. The upper portion of the discharge passageway is preferably contracted, as shown in Fig. I.

3 designates a screen arranged above the 110 discharge passageway and secured by means of a threaded ring 4.

The adjustable means for retarding the flow of ink to the brush preferably comprises a body of absorbent packing material 5, such for example as lamb's wool or other fibrous material, and an adjusting plug 6 screwed into the ink passageway at a point below said packing material. This adjusting plug is preferably provided with a passageway 7 through which the ink passes in flowing from the reservoir to the brush. Since the ink must also flow through the packing material 5, it will be apparent that the rate of flow may be regulated by compacting or loosening said material, and this may be accomplished by adjusting the screw plug 6. The brush may be readily removed from the brush holder to expose the plug 6. A notch 8, formed in the lower end of the plug 6, is adapted to receive a screw driver.

The packing material 5 must expand and contract in response to movements of the adjusting plug 6, and to insure the most desirable results this body of material should be free to expand and contract uniformly throughout, instead of being permanently compacted at some points or permanently compressed in the ink passageway. A body of elastic and absorbent material, such as lamb's wool, will expand and contract freely and uniformly in response to the adjustments of the screw plug, and I have found that such material is a desirable means for retarding the flow of ink from the reservoir.

In addition to a suitable body of packing material 5, the preferred form of the invention includes an expansible spiral spring 9 arranged in the packing chamber, the fibrous packing material being secured to said expansible spring, as shown in Fig. V. By interweaving the expansible spring and packing material I produce an expansible

body that will expand and contract freely in response to the movements of the adjusting plug, and since the packing material is secured to the various coils of the spring it will be positively loosened or compressed throughout the packing chamber in response to movements of the adjusting plug 6.

When the device is in service, the ink is wiped from the lower end of the brush, and ink will flow from the reservoir to compensate for the displacement at the brush. Since the ink is retarded by the packing material, the flow of ink is not rapid, the rate of flow being just sufficient to keep the brush saturated at the point where it engages the article to be marked. I have found in practice that the packing material may be adjusted to prevent the ink from dripping from the brush when the device is laid horizontally on its side. If desired, the packing may be so adjusted that the movements to which the brush is subjected in service will cause the ink to flow constantly through the compressed packing material; or, if preferred, this packing material may be so adjusted that it will be necessary to shake or jar the brush occasionally to obtain the desired flow. It will be apparent that the rate of flow may be regulated very accurately by adjusting the plug 6.

I claim:-

In a fountain brush, a liquid reservoir, a body of packing material for retarding the flow of liquid from said reservoir, an expansible spring to which said body of packing material is secured, said body of packing material being adapted to expand and contract with said spring, and means for adjusting said spring and packing material to regulate the flow of liquid from said reservoir.

CHRISTOPHER A. GARVEY.
